UNITED STATES PATENT OFFICE.

SAMUEL SOLOMEN LEVY, OF MATTAPAN, MASSACHUSETTS, ASSIGNOR TO SARAH LEVY, OF BOSTON, MASSACHUSETTS.

BUILDING CONSTRUCTION.

1,424,172.

Specification of Letters Patent. Patented Aug. 1, 1922.

Application filed October 30, 1920. Serial No. 420,587.

To all whom it may concern:

Be it known that I, SAMUEL SOLOMEN LEVY, a citizen of the United States, and resident of Mattapan, county of Suffolk, 5 State of Massachusetts, have invented an Improvement in Building Construction, of which the following description, in connection with the accompanying drawing, is a specification, like characters on the drawing 10 representing like parts.

This invention relates to building construction and particularly to building construction involving the use of blocks of cement or cementitious material. The object 15 of the invention is to provide a building block of novel form which can be readily laid up in the form of a wall and which is constructed so that when the blocks are thus laid up they can be readily secured together 20 simply by the insertion of cement or mortar in aligned grooves in adjacent blocks.

In order to give an understanding of my invention I have illustrated in the drawings some selected embodiments thereof which 25 will now be described after which the novel features will be pointed out in the appended claims.

Fig. 1 is a perspective view of the corner of a wall formed of building blocks embodying my invention.

Fig. 2 is a front view of a portion of a wall.

Fig. 3 is an end view of Fig. 2.

My improved building blocks are indicated at 7, in Fig. 1. Each block is made of cement or some suitable cementitious substance and may have any desired shape or size. Each block is formed on both its top face and its bottom face with a groove 35 which is aligned with a corresponding groove in the block beneath or directly above when the wall is laid up. These grooves are shown at 2 in Fig. 1, and each groove extends only partially across the block, said 40 groove terminating at a point near the front face of the block but not extending clear to the front face. These grooves 1 and 2 will preferably be dovetailed in shape and I will also preferably employ two 45 grooves in each face, said grooves being so situated relative to each other that the distance between the grooves on any face is twice the distance between each groove and the end of the block.

50 Where this arrangement of grooves ex-

ists the blocks may be placed one on the other so that they will break joints as shown in Figs. 1 and 2 and in each case the grooves on the bottom of any block will come into alignment with the grooves on 60 the top of the block beneath. After the building blocks have been laid up one on the other to form the wall then mortar or some other suitable cement or binding material 4 is inserted into the aligned 65 grooves as shown in Fig. 1. When the mortar or cement 4 sets the blocks will be firmly locked together thus making a rigid wall structure.

I may, if desired, form each block with a 70 rabbet 3 along either its top or its bottom edge at the front thereof. This rabbet may extend along the top edge merely or may also be formed along one of the vertical edges. Where this rabbeted structure is employed 75 it is my intention to fill the grooves formed by the rabbets with cement or mortar 5, after the blocks are laid this giving the completed wall the appearance shown in Fig. 2.

In Fig. 1, 6 indicates a foundation on 80 which the wall is laid.

Where the wall is built by laying the blocks so that they break joints it will be necessary to employ a block of one-half length as shown at 17 in some places. This 85 one-half length block however will have the grooves 1 or 2 therein properly situated to come into alignment with the grooves in the full length blocks when the latter are laid.

One advantage of my invention is that a 90 wall can be built up by simply placing the blocks on each other and without the necessity of providing a bed of mortar or cement for each block as it is laid. Since the blocks 95 are all made perfectly true a wall can be built up perpendicularly by unskilled labor and after the blocks are laid up the grooves can be filled with cement or mortar.

I claim:

1. A building block of cement having on both the top and bottom faces two dovetail grooves extending transversely from the inner face part way only to the outer face, said grooves being placed so that the distance between the grooves on any face is 105 twice that between each groove and the end of the block, whereby when the blocks are laid up in a wall with the blocks in adjacent courses breaking joint the two grooves in 110

the top face of any block in one course are in alignment with the grooves in the meeting ends of two blocks in the course above, all of the grooves being open at the inner 5 face of the block so that the blocks may be laid up dry and subsequently mortar or cement may be forced into the aligned grooves to bond the blocks together.

2. A wall formed of a plurality of building blocks laid one on the other with the blocks on adjacent courses breaking joint, each block having on both the top and bottom faces two dove-tail grooves which are so situated that the distance between the 10 15 grooves is twice the distance between each

groove and the end of the block, whereby the two grooves in the top face of a block in any course are directly beneath and communicate with grooves in two blocks of the adjacent course, said grooves being open at 20 the inner face of the wall and extending part way only to the outer face whereby said grooves are closed at the outer face, and cement or bonding material filling the aligned grooves and tying the blocks together.

In testimony whereof, I have signed my name to this specification.

SAMUEL SOLOMEN LEVY.
